UNITED STATES PATENT OFFICE.

BENJAMIN KAYE, OF BROOKLYN, NEW YORK.

DESIGN FOR A DOLL.

Application filed July 16, 1924. Serial No. 10,162. Term of patent 3½ years.

To all whom it may concern:

Be it known that I, BENJAMIN KAYE, a citizen of the United States, residing at borough of Brooklyn, city of New York, county of Kings, and State of New York, have invented a new, original, and ornamental Design for Doll, of which the following is a specification, reference being had to the accompanying drawing, forming a part thereof, in which—

Fig. 2 is a side elevation thereof; and
Fig. 3 is a rear elevation thereof.

I claim:

The ornamental design for a doll blowing a horn, substantially as shown.

BENJAMIN KAYE.
